ARTHUR I. FISCHER, OF CLEVELAND HEIGHTS, OHIO, ASSIGNOR TO GLAUBER BRASS
MANUFACTURING COMPANY, OF CLEVELAND, OHIO, A FIRM.

SANITARY DRINKING-FOUNTAIN.

1,242,538.

Specification of Letters Patent.

Patented Oct. 9, 1917.

Application filed June 1, 1915. Serial No. 31,386.

To all whom it may concern:

Be it known that I, ARTHUR I. FISCHER, a citizen of the United States, residing at Cleveland, in the county of Cuyahoga and 5 State of Ohio, have invented certain new and useful Improvements in Sanitary Drinking-Fountains, of which the following is a specification.

This invention relates to an improvement 10 in sanitary drinking fountains, and the invention consists in a fountain constructed and operating substantially as shown and described and particularly pointed out in the claims.

15 In the accompanying drawings, Figure 1 is a side elevation of the fountain and Fig. 2 is a sectional elevation thereof. Fig. 3 is a detail in side elevation of the discharge column.

20 Fig. 4 is a detail of a plug valve which seats in the bottom of the said column. Fig. 5 is a side elevation of the body of the fountain with all the other or attachable parts removed. Fig. 6 is a cross section of 25 the body looking down on line 6—6, Fig. 5. Fig. 7 is a plan view of the valve shown in Fig. 4 with the lock nut thereon.

The device constitutes a complete article 30 of manufacture and sale as seen in Figs. 1 and 2 and all the parts are screw threaded or socketed in position, as shown, so that they are easily assembled and adjusted. Furthermore, all the parts are mounted on the body B, which has a screw threaded 35 opening in its bottom to connect the water supply pipe P therewith and a waste channel 2 down at its side. The pipe P discharges into a chamber 3 in the middle of body B, which has a comparatively small 40 opening 4 in its top discharging into a tubular neck or extension 6 projecting some distance above said opening and inclosing the same about its bottom, and said neck has a plurality of discharge orifices 5 through the same laterally above its base 45 and an external thread about its base beneath said orifices and internal thread above said orifices. The said neck is enlarged in its threaded portion as compared with the 50 remainder of said neck, and a plug valve V is externally threaded to adjustably occupy seating relations with the seat therefor about the top of opening 4 and within the bottom of said neck. The lower portion of 55 the said valve is annularly reduced opposite

the discharge orifices 5 to provide a space in which the inflowing water may distribute itself about said valve to said orifices, whence the water flows upward within the sleeve 8 which carries the nipple n through 60 the shallow annular space between said neck 6 and said sleeve as plainly shown in Fig. 2, and which elements 8 and n constitute the discharge column.

The so-called sleeve 8 is internally threaded in its lower portion to engage upon the thread about the base of the valve containing neck 6 and its upper portion is slightly flared inside to provide a seat for the nipple n and wherein the nipple is permanently 65 secured. Preferably, the nipple is of china or porcelain or its equivalent, but may be of brass or any other metal, and the overflow cap C is trumpet shaped as shown and has a metallic socket member S in which it 70 is permanently seated and sealed. The said socket has a screw thread about its bottom engaged in annular internally threaded flange 9 on the top of body B. The said cup and socket are removable together as 75 one piece, as also is the column comprising nipple n and its sleeve support 8, and the valve is rendered available for removal or adjustment when the said parts are detached.

The said valve is provided with a lock nut 10 which bears on the top of neck 6 and holds the valve securely in any adjusted position relatively to the tapered seat above opening 4, and no change or variations in the flow of water can occur after the lock nut 10 has been tightened. Without lock nut 10, a gradual shift or change in position of the valve plug takes place in time, due to the water pressure and outflow about the valve. The internal screw thread at the lower end of tube 8 also extends to approximately the same height as neck 6 and as the space between this neck and the threaded surface of the tube is 90 relatively shallow the outflow of water tends to follow the screw thread. The parts n and 8 and C and S, respectively, being practically as one piece each, they are easily handled and both have close threaded engagement with the top of body B, as described. As to the shape of the said body it may be said that the shape or style thereof can be more or less varied and not depart from the invention, but the threaded 95 100 105 110

supports for the sleeve 8 and the socket S are essential as also is the neck 6 and the construction to receive and operate valve v.

What I claim is:

- 5 1. A sanitary fountain as described having a body provided with a tubular extension on its top and an inlet opening in the bottom of said extension having a valve seat and external screw threads at its base and discharge orifices at its side above said external threads and valve seat, a plug valve seated in said extension and adapted to engage said seat and close said inlet opening, a lock nut for said valve engaged with the 10 top of said extension, and a discharge column seated over said extension in screw engagement with its base threads and apart from said orifices.
- 15 2. A sanitary fountain as described comprising a body having a screw-threaded inlet centrally at its bottom and a discharge passage at one side and a tubular projection open at its bottom to said inlet passage and provided with a valve seat in its bottom and orifices through its side above said seat, in 20 combination with a plug valve adjustably engaged within said projection and having

an annularly reduced portion opposite said orifices, a lock nut sleeved upon the upper end of said valve in seating engagement 30 with the top of said projection, and a water column screwed upon said body about the base of said projection.

3. A sanitary fountain as described having a water delivery column and a body 35 with a fluid passage through the same opening into said column, a tapering overflow cap of vitreous material surrounding said column, a metal socket member screw-engaged with said body having a relatively 40 long extension supporting the tapering portion of the cap, a screw valve adjustably seated within said column and adapted to close said opening and a nut on said valve adapted to lock the same in adjusted position, and said body having a screw-threaded inlet centrally at its bottom and a relatively short discharge spout adjacent said inlet.

In testimony whereof I affix my signature in presence of a witness.

ARTHUR I. FISCHER.

Witness:

Geo. E. KRICKER.
